TOY OF THE FLUENT MATERIAL
OPERATIVE TYPE

Paul A. Williams, Snyder, N. Y.

Application October 21, 1950, Serial No. 191,391

8 Claims. (Cl. 46—115)

1

This invention relates to an improvement in toys of the fluent material operative type and proposes a novel toy in which provision is made for the flow in countercurrent relation of immiscible fluids of different specific gravities, the heavier fluid being in any case a liquid and the lighter fluid preferably being a gas, e. g. air. The gas will flow upward through the liquid in the form of bubbles and will thereby produce a mystifying visual effect. The flow of the bubbles through the liquid will be at a frequency sufficient for the effect desired, at a relatively constant rate, and through a definite time period sufficiently prolonged. It will, of course, be understood that the fluids are sharply differentiated as to color in order that the visual effect may be suitably pronounced.

The invention is characterized by a vertical tubular column which at its ends is connected in sealed relation to reservoirs, one in an upper relation and the other in a lower relation, the column and the reservoirs constituting a sealed container for the fluents and the column being in such communication with each reservoir that the liquid will be discharged into the lower reservoir at a point below the point at which the air escapes from the lower reservoir into the column, the air thus escaping passing thence into the upper reservoir and rising through the body of liquid therein which is contemporaneously flowing by gravity from the upper reservoir into and downwardly through the column. Each reservoir is fashioned to serve as a supporting standard for the toy which, as vertically positioned, is reversible in order that a completed cycle of operation may be immediately repeated. The reservoirs are preferably opaque whereby to conceal the physical features by which the mystifying effect of the toy is achieved and hence to enhance the effect. The tubular column may be wholly transparent throughout its entire extent or may be transparent at intervals, that is to say, may have transparent zones or windows separated by opaque zones, the transparent and opaque zones jointly producing a flashing visual effect.

The structural features of the toy are coordinated to the contained liquid. The liquid has a degree of viscosity suitable for the purposes of the invention, that is to say, it will intrinsically have a relatively slow rate of flow and its rate of flow from the upper reservoir into the column and thence into the lower reservoir will be further retarded by the restriction, relatively to the areal horizontal section of the column, of the liquid flow openings or passages between the column and

2

the reservoirs. The surface tension of the liquid is such that it will retard the formation of the bubbles of air to a degree whereby the air bubbles, which have a relatively slow rate of flow through the liquid in the column, will be lineally spaced from one another to a suitable extent. The rate of flow of the air bubbles through the column is governed by the viscosity of the liquid and may ideally be three bubbles for every two seconds of time. Of course, the rate of flow of the bubbles may, at choice, be greater or less than the suggested rate in accordance with the selection of the viscosity of the liquid. The amount of liquid is sufficient to fill either of the reservoirs and the vertical column.

The time of the cycle of flow of the air bubbles is ideally through several minutes, e. g. from three to five minutes. The time selection depends on the rate of flow of the liquid and the relative proportions of the structural parts of the toy. For example, assuming a liquid of a desirable degree of viscosity, a toy having a length of approximately eight inches may have its parts so relatively proportioned that the time for the completion of a cycle of operation will be of the order of five minutes.

In all of the embodiments of the invention the toy is constructed whereby the liquid which passes from the column into the lower reservoir has within the chamber provided by the lower reservoir a downward path of flow which terminates at a point below the opening which provides for the escape of the air from the lower reservoir into the column.

In the accompanying drawings:

Figure 1 is an elevation of a toy in accordance with the invention.

Figure 2 is a vertical central section of one embodiment of the toy.

Figure 3 is a detail sectional view of the lower reservoir of a toy of the external form shown in Figure 1 when the toy is in the position shown in that figure, this figure as compared with Figure 2 illustrating a modification.

Figure 4 is a perspective view of one of the two similar half sections of which the toy shown in Figure 3 is composed.

Figure 5 is a view similar to Figure 3 but showing another modification.

Figure 6 is a detail horizontal section on the line 6—6 of Figure 5 looking in the direction of the arrows.

Figure 7 is a view similar to Figures 3 and 5 but showing still another modification.

Figure 8 is an elevation, partly broken away

and showing still another modification wherein the toy has a double column arrangement and the columns are provided with transparent windows separated by opaque zones.

Figure 9 is a detail horizontal section along the line 9—9 of Figure 8.

Referring to Figures 1 and 2:

These figures show an embodiment consisting of the essential structural elements of a vertical tubular column 1 and closed reservoirs 2 and 3 at each end of the column and with which the column is connected in sealed relation, the reservoirs being mutually spaced to an extent sufficient for the purposes of the toy, that is to say to an extent whereby the column has between them a sufficient length, e. g., four or five inches.

The column 1 may be transparent throughout its extent, or, as shown in Figure 8 and later described in detail, may have spaced transparent portions or windows separated by opaque portions. The column and the reservoirs are made of non-breakable plastic material.

The reservoirs in each instance provide supporting standards for the toy whereby the toy, standing vertically, is reversible. Therefore, in each instance, the reservoirs may be adapted as to outline and surface ornamentation for an amusing display effect. For example, in the construction shown in Figure 1 the reservoir 3 is spherical and each face may be painted to present a suitable picture, i. e., the head of a cat as shown in Figure 1.

The reservoir 3, as of spherical formation, carries a flat faced terminal boss 4 by which the reservoir functions as a supporting standard when the toy is inverted from the position of Figure 1.

In the embodiment shown in Figure 2, column 1 extends into and through the chambers provided by the reservoirs, its ends being seated in sealed relation in recesses 5 formed respectively in the base of the reservoir 2 and in the terminal boss 4.

One of the reservoirs, e. g. the reservoir 2, is provided with an opening 6, normally closed by a plug 7, through which the liquid may be introduced into the toy.

The portions of the column 1 which extend into and through the chambers provided by the reservoirs are designated as 8 and in each instance are formed with spaced openings 9 and 10, the openings 9 being in mean relation and the openings 10 in extreme relation. These openings in each instance have an areal extent which is a minor fraction of the areal extent of the column in horizontal section, the openings, as liquid flow openings, between the column and the reservoir, therefore, providing for relatively restricted communication between these parts.

The requirements of the liquid are that it shall be translucent, that it will flow downward through the column at a relatively slow rate and that it will oppose such resistance to the formation of the air bubbles and to the countercurrent upward flow of the bubbles that the mystifying visual effects of the toy will be achieved. The liquid may be a simple syrup suitably colored, or it may be an oil of suitable viscosity and color. In either case important factors in causing the suitably slow gravitational flow of the liquid through the column are its viscosity and the restricted liquid flow openings between the column and the reservoirs.

In Figure 2 the liquid is designated A and the air is indicated at B. As shown in Figures 1 and 2 the reservoir 2 is the supporting standard. These figures assume the operative condition of

the toy, that is to say, as shown in Figure 2 they assume a body of liquid A within the upper reservoir 3. The liquid flows through the opening 9 (within the reservoir 3) into and through the column 1 and from the portion of the column 1 within the chamber provided by the lower reservoir 2 through the opening 10 into this reservoir. As the liquid accumulates in the reservoir 2 it will, of course, displace the air B which will pass in the form of bubbles B' through the column 1 and thence into the reservoir 3 through the opening 10, the air occupying the space above the body of liquid A.

With the toy positioned as shown in Figure 2, the flow of the fluids A and B as above described will be continued for a period of several minutes and will cease when the liquid A is drained from the reservoir 3 and the air is displaced from the reservoir 2. During the flow of the liquid A from the reservoir 3 through the column 1 and into the reservoir 2, the bubbles B' will pass upwardly through the column 1 at a comparatively slow rate of flow as above explained.

When the cycle of flow of the fluids with the toy in the position shown in Figures 1 and 2 has been completed as above explained, the toy is inverted and the cycle of flow of the liquids is repeated.

Various modifications may be provided to cause the flow of the fluids in the manner above described. Three modifications are shown in Figures 3, 5 and 7 respectively.

In the construction shown in Figure 3 the column 1 does not extend into the reservoirs. Instead, at its points of connection to the reservoirs 2 and 3 it is provided with terminal webs 11, athwart the column and athwart the respective reservoirs, each web 11 being in overhanging relation to the particular reservoir in the lower position. The web 11 shown in Figure 3 overhangs the reservoir 2. The webs 11 are each provided with an opening 12 which is preferably spaced from the wall of the column, the openings 12 interchangeably functioning for the flow of air or liquid accordingly as a web may be in lower or upper relation. The air escapes through the opening 12 of the lower web and flows upwardly in the form of bubbles through the column 1. Each web 11 is formed with an inclined wall 13 adjacent and parallel to a portion of the wall of the reservoir. The wall 13 in combination with the adjacent portion of the wall of the reservoir provides a passage 14 which at one end is in open communication, as at 15, with the column 1 and at its opposite end is in open communication, as at 16, with the reservoir. The liquid flows from the uppermost reservoir through the opening 12 and into the column 1 whence, following the line of least resistance, it flows through the lower passage 14 into the lower reservoir. The air which is displaced by the accumulation of liquid in the lower reservoir escapes into the column 1 through the opening 12 and from the column 1 into the upper reservoir through the upper passage 14. The opening 16 through which the liquid escapes from the lower passage 14 into the lower reservoir is suitably below the opening 12 through which the air escapes from the lower reservoir into the column 1. The liquid flow openings between the column and the reservoirs provide the restricted communication above described, the liquid flow opening 15 preferably being of less areal extent than the adjacent opening 12. The flow of the fluids is similar to that above

described in connection with the construction shown in Figure 2.

The modification shown in Figures 5 and 6 is generally similar to the construction shown in Figure 3. In Figure 5, however, the wall 13 and passage 14 are not employed. Instead, the column 1 is provided with terminal fingers 17 which extend for a suitable distance into the reservoirs, the fingers 17 being in vertical alinement with the wall of the column 1 and conforming in cross sectional curvature. This modification utilizes the webs 11 and the openings 12 above described. Each web 11, however, is provided with an opening 18 which adjoins the corresponding finger 17 and is preferably of less diameter than the opening 12. The liquid readily flows through the opening 18 and by reason of its wetting quality and capillary attraction flows along the lower finger 17. Oil has a very pronounced natural wetting quality. If the liquid be a simple syrup the desired wetting quality can be obtained by an additive in the nature of a synthetic surface action compound, for example, dioctyl sodium sulfosuccinate which is currently sold under the trade name "Aerosol O T." The stream of liquid discharges into the lower reservoir from the lower end of the finger 17 and its discharge point is suitably below the corresponding air escape opening 12. The flow of the fluids is similar to that above described in connection with the construction shown in Figure 2.

In the modification shown in Figure 7 the wall of each reservoir has a gentle curve, as shown at 19, adjacent the corresponding end of the column 1, the combined curvature of the adjacent parts of the walls of the column 1 and the reservoir being generally of ogee outline. In this modification each web 11 is provided with the openings 12 and 18, as described in connection with Figure 5, the opening 12, as in the embodiment of Figure 5, being suitably spaced from the wall of the column and the opening 18 adjoining the wall of the column at the point where the column joins the reservoir. The finger 17 of the construction shown in Figure 5 is dispensed with and the curved portion 19 of the wall of each reservoir is relied upon to prescribe the path of flow of the liquid from the column into the lower reservoir, the liquid as it flows through the opening 18 flowing along the curved wall portion 19 of the reservoir by reason of its wetting quality and capillary attraction. The curvature of the wall of the reservoir may, of course, be at any angle relatively to the column 1 which is suitably less than a right angle, a gentle curvature being preferred. In this modification the point of discharge of the liquid into the reservoir from the path prescribed by the curved wall portion 19 can be said to be dictated by the plane of the surface level of the accumulated liquid in the reservoir, that is to say the liquid by its wetting quality and capillary attraction can be said to be drawn to that plane which as the accumulation increases progressively moves upward. Thereby, in any event, the discharge point of the liquid flowing along the wall portion 19 into the body of liquid in the lower reservoir is suitably below the opening 12 through which the displaced air escapes from the lower reservoir into the column 1.

From a manufacturing standpoint each of the four constructions above described may be made in companion longitudinally extending half sections. One such half section, corresponding to the form shown in Figure 3, is illustrated in Figure 4. As made of plastic material the companion

half sections, in accordance with well-known practice, are impregnated with a solution which, when the half sections are fitted together in matching relation, constitutes in effect a permanent sealing weld between them.

In the four forms above described the toy includes but a single column 1. The toy may, however, have more than one column 1. This is sufficiently illustrated in Figure 8 wherein the toy is provided with two columns 1a, each of which corresponds structurally and functionally to the column 1 of the constructions previously described. The provision of more than one column enables the toy to be made in a variety of entertaining forms or designs. For example, as shown in Figure 8, the columns 1a represent the legs and raised arms of a toy figure in the form of a clown, which in the position shown supports an overhead receptacle (the upper reservoir) and in the reversed position will appear as performing a hand stand and supporting an overhead receptacle upon its feet. With two columns the reservoirs 2 and 3 are provided in duplicate, one for each column, by means of a separating partition 20, each reservoir functioning in the same manner as the reservoirs in the construction previously described. The provision for causing the circulation of the fluids in the manner above described may be of any suitable form, the form shown in Figure 3 being selected for example and being indicated by dotted lines. Figure 8 also shows the columns as having transparent zones or windows 1b and intervening opaque zones 1c, the opaque zones being provided by the application of suitable paint.

As a manufacturing proposition the construction shown in Figure 8 may be made in matching half sections which are joined together in the manner above explained, their jointure being sufficiently indicated in Figure 9. The half sections are provided with inwardly projecting ribs 21 which delimit the interiors of the columns 1a and also delimit other spaces which are without function but are provided simply for the purpose of lightness of weight.

I claim:

1. A toy of the fluent material operative type consisting of a vertical transparent tubular column and a reservoir connected to the column at each end thereof, the column and the reservoirs constituting a sealed container for immiscible fluids of different specific gravities, the heavier fluid being a liquid which partially fills the container, each reservoir being formed to provide a supporting standard for the toy and thereby to enable the reversibility of the toy in a vertical position, the reservoirs being interchangeably in upper and lower relation accordingly as the toy may be in an initial vertical position or a reversed vertical position, the toy being provided with two openings which establish communication between the column at each end thereof and the reservoir connected to that end, the openings being of restricted areal extent relatively to the areal extent of the column in horizontal section and severally providing for the flow of the liquid from the upper reservoir downwardly through the column and into the lower reservoir and for the escape of the lighter fluid from the lower reservoir upwardly through the column and into the upper reservoir, the toy being formed whereby the liquid which passes from the column into the lower reservoir through the opening provided for such passage has within the chamber provided by the lower reservoir a down-

ward path of flow which terminates at a point below the opening which provides for the escape of the lighter fluid from the lower reservoir into the column.

2. A toy as set forth in claim 1 wherein the liquid has a selected degree of viscosity and a pronounced wetting action and the lighter fluid is air.

3. A toy as set forth in claim 1 wherein the walls of the reservoirs are opaque.

4. A toy as set forth in claim 1 wherein the column extends through the reservoirs and has a sealed connection with the reservoirs, the portions of the column within the reservoirs being provided with the openings which severally function for the flow of the liquid and the lighter fluid.

5. A toy as set forth in claim 1 wherein the column has terminal webs in which the openings are formed and a wall is arranged in the reservoirs in parallel relation to adjacent portions of the walls of the reservoirs to provide passages, the lower passage serving for the flow of the liquid from the column into the lower reservoir, the opening for the flow of the liquid from the column being at the upper end of the passage.

6. A toy as set forth in claim 1 wherein the column has terminal webs in which the openings are formed, a finger projects from the column into each reservoir, and the opening which provides for the passage of the liquid from the

column into the lower reservoir adjoins the finger, the latter prescribing a path of flow for the liquid from the column into the lower reservoir.

5 7. A toy as set forth in claim 1 wherein the column has terminal webs in which the openings are formed, the wall of each reservoir has a gentle curve adjacent the corresponding end of the column and the opening through which the liquid flows from the column into the reservoir adjoins the reservoir wall portion of gentle curvature, such reservoir wall portion prescribing a path of flow for the liquid from the column into the lower reservoir.

10 8. A toy as set forth in claim 1 wherein the transparency of the column is interrupted by opaque zones, the column thereby having a series of transparent windows and separating opaque zones.
